Primary Examiner—Louis S. Zarfas*Assistant Examiner*—Frank Martinez*Attorney, Agent, or Firm*—Flynn, Thiel, Boutell & Tanis, P.C.[57] **CLAIM**

The ornamental design for a CD-Box, as shown and described.

DESCRIPTION

FIG. 1 is a perspective view of a CD-Box showing my new design;

FIG. 2 is an enlarged detail of one of the corners of the CD-box;

FIG. 3 is a perspective view showing the CD-Box in a partially open position;

FIG. 4 is an exploded view of the CD-Box;

FIG. 5 is a perspective view thereof with a partial sectional view;

FIG. 6 is an enlarged sectional view of one of the corners thereof;

FIG. 7 is a top plan view of FIG. 1;

FIG. 8 is a right side elevational view thereof;

FIG. 9 is a front elevational view thereof;

FIG. 10 is a top plan view of a bottom element of the CD-box;

FIG. 11 is a bottom plan view of FIG. 1;

FIG. 12 is a left side elevational view of FIG. 7; and,

FIG. 13 is a rear view of FIG. 7.

The broken line showing of the CD in FIGS. 3 and 4 and the hand in FIG. 4 is for illustrative purposes only and forms no part of the claimed design.
